UNITED STATES PATENT OFFICE

LUDWIG SCHÖN, OF VIENNA, AUSTRIA-HUNGARY.

SAFETY-SPOUT FOR RECEPTACLES CONTAINING VOLATILE INFLAMMABLE LIQUIDS.

No. 809,634.

Specification of Letters Patent.

Patented Jan. 9, 1906.

Application filed March 14, 1901. Serial No. 51,203.

To all whom it may concern:

Be it known that I, LUDWIG SCHÖN, a subject of the Emperor of Austria-Hungary, residing at Vienna, in the Province of Lower Austria and Empire of Austria-Hungary, have invented a new and useful Improvement in Safety-Spouts for Receptacles Containing Volatile Inflammable Liquids, of which the following is a specification.

10 My invention relates to receptacles for keeping and carrying volatile inflammable liquids—such as spirits, ether, benzin, sulfid of carbon, and the like; and it has for its object to provide a closing device for the orifices of such receptacles which in the case of the vapors issuing from the receptacle being accidentally ignited with certainty prevents combustion from spreading into the interior of the receptacles.

20 According to my invention the inlet and outlet orifices to be provided with the safety-spout have necks inserted into them, a diaphragm of fine wire fabric or finely-holed sheet metal being interposed into each neck.

25 Between the diaphragm and the receptacle the passage or bore of the neck is by preference narrowed and adapted to be controlled by a cylindric slide-valve screwing into the side of the neck, across this latter, and pro-

30 vided with a conic front end, to which corresponds a seat formed in the side of the passage. The free end of the neck has its outside provided with male screw-threads and its inside with female screw-threads in order 35 to admit of a cap being screwed on, the cylindric rim of which has female screw-threads, while its central nipple has male screw-threads. Between the cylindric rim and the central nipple a suitable packing is secured to 40 the cap.

In the annexed sheet of drawings, Figure 1 is a sectional elevation of the lower part of a sheet-metal cask the outlet-orifice of which is provided with my safety-spout; and Fig. 2 45 is a sectional elevation of a sheet-metal can, into which the inflammable volatile liquid is allowed to flow from the cask. Figs. 3 and 4 are sectional views of a screw-cap and screw-stopper, respectively.

50 It will be seen that a neck or tube is soldered into the outlet-orifice *a* of the sheet-metal barrel *b*, the said neck being composed of two lengths *c* and *d*, screwed together and finally connected by solder. Into the inner

55 joint between the two lengths *c* and *d* is inserted the diaphragm *f*, made of fine and dense wire fabric or of finely-perforated sheet metal. This diaphragm is either made of a metal not subject to oxidation or provided with a coating which prevents oxidation, as its being 60 destroyed by oxidation in only one point would render it ineffective.

Between the diaphragm *f* and the cask *b* the passage or bore of the neck is narrowed at *g* in order to adapt it to be closed by means of 65 a pin or cylindric slide-valve *h* of greater diameter than the channel *g* and screwing into a bore crosswise to the said channel. The front end of the pin *h* is made conical and enters a correspondingly-shaped seat formed in 70 the side of the passage *g*. It will be seen that by partly unscrewing the pin *h* one may more or less withdraw its conical point from corresponding seat, and thereby open the passage to any desired degree. The outer 75 end of the valve *h* is protected by a screw-cap *j*, provided with a hole *i*, through which a cord or wire *y*, destined to carry a leaden seal *x*, may be threaded. When such a cord or wire *y* is used for preventing the valve *h* from 80 being opened during transport or storage, the said cord or wire *y* is also passed through the eye *z*, made integral with the length *c* of the neck.

The outer end of the outlet-neck is under 85 ordinary circumstances closed by a screw-cap *k*, Fig. 3, provided at the center of its inside with a screw-threaded nipple *l*. To the female screw-threads of the rim of the cap correspond the male threads of the outside of 90 section *d* of the neck, while the male threads of the nipple *l* are destined to engage the female threads at the inside of the length *d* of the neck. Between the nipple *l* of the cap *k* and its rim the bottom of the cap is at *m* covered with a packing chosen according to the 95 nature of the liquid to be kept in the receptacle. In Fig. 1 it is supposed that this cap *k*, commonly closing the outlet-neck and provided with a solid bottom, has been removed 100 and replaced by a cap-*n'*, into a central orifice of whose bottom a spout *n* is soldered. The lower end of the said spout *n* is again provided with the safety device comprising 105 the tube or neck, consisting of the two lengths *c* and *d* and the diaphragm *f*, clamped between them.

The can *o*, into which the volatile inflam-

mable liquid coming from the cask *b* is to flow, has its inlet-orifice again provided with the neck consisting of the lengths *c* and *d*, between which the wire-fabric diaphragm *f* is 5 clamped and which is adapted to be closed by a screw-cap *k*, Fig. 3, with a central screw-threaded nipple *l*. The spout *p* of the can *o*, too, has its mouth fitted with the tubes *c* and *d*, screwed together and clamping the sieve- 10 diaphragm *f*. The screw-plug *v*, Fig. 4, having a packing *u*, secured to its collar, serves for closing the spout *p*.

With the described safety-stopper one may 15 kindle benzin flowing out from the spout *n* and allow it to flow in the burning state into the can *o* without any fear of endangering the contents of the can or the cask.

The sieve-diaphragms *f* in inlet-necks are 20 to advantage made cup-shaped, turning the convex side downward, and provided with a plane sieve-flange, through which the air displaced by the liquid which enters the can or receptacle can escape.

When filling a receptacle provided with the 25 described safety-stopper, care must be taken that the level of the liquid should be placed below the sieve-diaphragm. Any surplus liquid poured in inadvertently should be decanted.

What I claim, and desire to secure by Let- 30 ters Patent of the United States, is—

1. In safety bungs and taps or spouts for receptacles for volatile inflammable liquids, the combination with the orifice of an outwardly-projecting neck, and a wire-gauze diaphragm inserted into the outer end of the neck, the said diaphragm having, in the clear 35 of the neck, a ring-shaped, plane, marginal portion and a shallow cup-shaped central portion, substantially as and for the purpose 40 described.

2. In a safety-tap for receptacles for volatile inflammable liquids, the combination with the tap-hole of an outwardly-projecting neck, a wire-gauze diaphragm inserted into 45 the outer end of the neck, a spout adapted to be secured to the neck, a wire-gauze dia- phragm inserted into the outer end of the spout, and a valve adapted to close the said neck between the receptacle and diaphragm, 50 substantially as and for the purpose de- scribed.

In witness whereof I have signed this specification in presence of two witnesses.

LUDWIG SCHÖN.
